US0D1105496S

(12) **United States Design Patent** (10) **Patent No.:** **US D1,105,496 S**
(45) **Date of Patent:** **** Dec. 9, 2025**

(54) **BUILDING BLOCK**

- (71) Applicant: **FASTBRICK IP PTY LTD**, High Wycombe (AU)
- (72) Inventor: **Mark Joseph Pivac**, Lesmurdie (AU)
- (73) Assignee: **FASTBRICK IP PTY LTD**, High Wycombe (AU)

(**) Term: **15 Years**

(21) Appl. No.: **29/943,373**

(22) Filed: **May 21, 2024**

(30) **Foreign Application Priority Data**

Nov. 21, 2023 (AU) 202317730

(51) **LOC (15) Cl.** **25-01**

(52) **U.S. Cl.**

USPC **D25/114**

(57) **CLAIM**

The ornamental design for a building block as shown and described.

DESCRIPTION

FIG. 1 is a top front perspective view of the embodiment of building block according to the present invention;

FIG. 2 is a bottom rear perspective view thereof;

FIG. 3 is a top view thereof;

FIG. 4 is a left-side view thereof;

FIG. 5 is the front view thereof;

FIG. 6 is a right-side view thereof;

FIG. 7 is a bottom view thereof; and,

FIG. 8 is a rear view thereof.

1 Claim, 2 Drawing Sheets
